Des. 211,782
Patented July 30, 1968

211,782

ENCLOSURE FOR ELECTRICAL EQUIPMENT AND THE LIKE

William L. Bright, 111 SW. Harrison, and Herbert N. Steinmeyer, 2419 SW. Richardson, both of Portland, Oreg. 97201, and James D. Coon, 4041 SW. 53rd Place, Portland, Oreg. 97221

Filed Nov. 15, 1967, Ser. No. 9,431

Term of patent 14 years

(Cl. D13—1)

FIG. 1

FIG. 2

FIG. 3

FIG. 1

FIG. 4

FIG. 5

FIG. 6

FIGURE 1 is a front elevational view of a first form of our design for an enclosure for electrical equipment and the like;

FIGURE 2 is a side elevational view of the design of FIGURE 1;

FIGURE 3 is a top plan view of the design of FIGURE 1;

FIGURE 4 is a front elevational view of a second form of our design for an enclosure for electrical equipment and the like;

FIGURE 5 is a side elevational view of the design of FIGURE 4; and

FIGURE 6 is a top plan view of the design of FIGURE 4.

In the design, the front and rear are identical, the sides are identical, and the bottom is open.

We claim:

The ornamental design for an enclosure for electrical equipment and the like, as shown and described.
